[57] CLAIM

The ornamental design for an optical magnetic disc cartridge, as shown and described.

DESCRIPTION

FIG. 1 is a bottom, front and right-side perspective view of an optical magnetic disc cartridge, showing our new design;

FIG. 2 is a front elevational view thereof;

FIG. 3 is a front elevational view thereof, shown with the shutter in the opened position;

FIG. 4 is a rear elevational view thereof;

FIG. 5 is a rear elevational view thereof, shown with the shutter in the opened position;

FIG. 6 is a left-side elevational view thereof;

FIG. 7 is a right-side elevational view thereof;

FIG. 8 is a top plan view thereof; and,

FIG. 9 is a bottom plan view thereof.

FIG.1

FIG.2
